UNITED STATES PATENT OFFICE.

AXEL EMANUEL SENOBÉ, OF NEGAUNEE, MICHIGAN.

TELEGRAPH TRANSMITTER.

Application filed December 31, 1926. Serial No. 158,272.

This invention relates to telegraph transmitters and more particularly to that type of telegraph transmitter employing a vibrating reed with a horizontally oscillating lever bearing contacts.

An important object of the invention is the provision of a device of this character such that the key may be readily transformed from the usual vibrating reed type of instrument to a double speed telegraph key.

A further object of the invention is the provision of a construction of this character which may be very readily and cheaply constructed, which will be durable and efficient in service and a general improvement in the art.

These and other objects I attain by the construction shown in the accompanying drawings, wherein for the purpose of illustration is shown a preferred embodiment of my invention and wherein:

Figure 1 is a plan view of a key constructed in accordance with my invention;

Figure 2 is a side elevation thereof;

Figure 3 is a section on the line 3—3 of Figure 2;

Figure 4 is a section on the line 4—4 of Figure 2.

Referring now more particularly to the drawings, the numeral 10 indicates a suitable base, at present indicated as constructed of conducting material. Arising from this base and electrically connected therewith is a support 11, to the upper end of which is secured a spring 12, the opposite end of which is secured through a block 13 to an operating lever or key 14. Between the block 13 and key lever 14 is secured the end of a spring 15, the outer end of which has secured thereto a bar 16 having arranged thereon a counterweight 17. The bar 16 bears a contact spring 18 adapted to coact with an adjustable screw contact 19 carried by and insulated from the base.

It will be noted that the spring 15 is attached at a point spaced from the inner end of the lever 14 and lies closely against this lever. This end of the lever, therefore, acts as a fulcrum about which the spring tensions when swung in one direction under the influence of the weight 17. This short-

ens the rebound action of the spring or that action which carries the contact spring 18 away from the contact screw 19. Adjacent the free end of the bar 16, a support 20 is disposed, this support being electrically connected with the base and having rotatably mounted thereon a latch 21 which, in one position thereof, engages the bar 16 to hold the same against movement transversely of the base and accordingly serves to prevent engagement of the contact 18 with the contact 19. An adjustable screw 22 opposes movement of the spring 15 in a direction permitting separation of the contacts 18 and 19. Upon the base are arranged binding posts 23 and 24, the binding post 23 being electrically connected with the base and the binding post 24 being electrically connected with the contact screw 19 by a contact strip 25 connecting the binding post with a support 26 upon which the contact screw 19 is mounted.

Arranged upon opposite sides of the key lever are standards 27 and 28 insulated from the base 10 and each having at their upper ends a contact screw 29 for coaction with the contact 30 upon the adjacent face of the key lever. The standard 27 is electrically connected with the binding post 24 by a bus 31 and electrically connected with the standard 28 is a switch 32 which may be shifted to a position where it electrically connects the standards 27 and 28. Electrically connected with the base is a second switch 33 which may be employed to connect the binding post 24 to the base and thus shorten the instrument.

The operation of the device is as follows: When the operator desires to employ the device as a semi-automatic key, the latch 21 is disengaged and the switch 32 moved to the open position. In this position, when the key contact 30 engages with the screw 29 of the standard 27, dashes may be formed, while when the key is moved to engage the contact 30 at the opposite side with the screw 29 of the standard 28, no circuit is completed at this point, but the vibration of the spring 15 or reed 16 will cause the contacts 18 and 19 to intermittently engage and disengage, forming the "dot" signal. When it is desired to employ the device as a simple key,

the latch 21 may be employed to lock the bar 16 against movement and the switch 32 left open. At this time, the horizontally swinging lever will complete the circuit through the binding screw 29 of the support 27. If desired that a double speed key be produced, the switch 32 is closed, while the bar 16 is locked against movement and by this operation, both the adjustment screws 10 29 are connected in the circuit, so that operation of the key lever 14 to bring the contact 30 into engagement with either thereof will cause completion of the circuit in the formation of a signal element.

15 It will be obvious that a single instrument actually includes three different types of telegraph keys, enabling an operator to shift from one form of sending to another, so that his hand may be rested. It will also 20 be obvious that because of the simplicity of the construction, the device may be very cheaply and at the same time durably constructed. Particular attention is directed to the fact that with the bar 16 locked, the 25 spring 15 acts to assist in tensioning the key lever 14 and in the maintenance thereof in the proper central position.

Since the construction hereinbefore set forth is capable of a certain range of change 30 and modification without materially departing from the spirit of the invention, I do not limit myself to such specific structure except as hereinafter claimed.

I claim:—

35 1. In a telegraph instrument, a key lever mounted to swing horizontally, a spring secured at its end only to the key lever the connection being at a point intermediate the ends of the key lever, the spring extending along one face of the key lever, a bar carried by the outer end of the spring, a spring contact carried by the bar, a second contact with which the spring contact is adapted to engage upon vibration of the bar when 40 the key lever is shifted a predetermined distance in one direction and adjustable means limiting the shifting of the key lever in said direction.

50 2. In a telegraph instrument, a key lever mounted to swing horizontally, a spring secured at its end only to the key lever the connection being at a point intermediate the ends of the key lever, the spring extending along one face of the key lever, a bar carried by the outer end of the spring, a spring contact carried by the bar, a second contact with which the spring contact is adapted to engage upon vibration of the bar when 55 the key lever is shifted a predetermined distance in one direction, an adjustable member limiting the shifting of the key lever in said direction and insulated from the second contact, a second adjustable member limiting movement of the key lever in the opposite direction and electri-

cally connected with the second contact, and a switch for electrically connecting the first named adjustable member with the second named adjustable member.

5 3. In a telegraph key, a base, a standard 70 arising from the base, a spring secured at one end to the standard, a key lever secured to the opposite end of the spring, a second spring secured at its end only to the key lever the connection being at a point intermediate the ends of the key lever, said second spring extending along one face of the key lever, a bar carried by the free end of the second spring, a spring contact carried thereby and a second contact with 75 which the spring contact engages upon vibration of the lever when moved a predetermined distance in one direction.

4. In a telegraph key, a base, a standard 80 arising from the base, a spring secured at one end to the standard, a key lever secured to the opposite end of the spring, a second spring secured at its end only to the key lever, the connection being at a point intermediate the ends of the key lever, said second spring extending along one face of the key lever, a bar carried by the free end of the second spring, a spring contact carried thereby, a second contact with which the spring contact engages upon vibration 85 of the lever when moved a predetermined distance in one direction, a third contact element limiting movement of the key lever in said direction and normally insulated from the second contact, a fourth contact 90 limiting movement of the key lever in the opposite direction and electrically connected with the second contact and a switch for electrically connecting the third and fourth contact elements.

5. In a telegraph key, a base, a standard 95 arising from the base, a spring secured at one end to the standard, a key lever secured to the opposite end of the spring, a second spring secured at its end only to the key 100 lever the connection being at a point intermediate the ends of the key lever, said second spring extending along one face of the key lever, a bar carried by the free end of the second spring, a spring contact carried 105 thereby, a second contact with which the spring contact engages upon vibration of the lever when moved a predetermined distance in one direction, a third contact element limiting movement of the key lever in said direction and normally insulated from the second contact, a fourth contact limiting movement of the key lever in the opposite direction and electrically connected with the second contact, a switch for 110 electrically connecting the third and fourth contact elements and means for latching the bar against movement in a position preventing engagement of the first and second contacts.

6. In combination with a telegraph instrument including a key lever and a vibratory reed element carried by the key lever for the formation of "dots", means for rendering said vibratory reed element inoperative, a pair of adjustable contact members limiting movement of the key lever in opposite directions one of which is connected in the circuit of the instrument and a switch for connecting the second contact in the circuit 10 of the instrument.

In testimony whereof I hereunto affix my signature.

AXEL EMANUEL SENOBE.
